UNITED STATES PATENT OFFICE

2,025,802

AIR CONDITIONER

Lachlan W. Child, Toledo, Ohio, assignor, by
mesne assignments, to Aeret Air Conditioner
Company, a corporation of Illinois

Application August 25, 1934, Serial No. 741,453

15 Claims. (Cl. 257—137)

This invention relates to air conditioners, and has as its object to provide a unit adapted particularly for air cooling, but adapted also for air heating with means for filtering the air. It relates particularly to what is sometimes termed a "floor type" unit, of an upstanding construction adapted to rest upon the floor of a room, enclosed in a suitable cabinet, or to be built into a wall of the room to be conditioned.

10 An important object is to provide such a unit which is relatively silent in operation. In this respect, the invention contemplates a belt driven, relatively slow speed centrifugal fan comprising simply an impeller of relatively large circumference, without any circumferential shroud.

Another object is to provide an arrangement in which the fan, although quite close to the discharge vent of the casing, and of a diameter much less than the length of the casing, will discharge a stream of air issuing fairly uniformly from the entire length of a vent the full length of the casing.

Another object is to provide ample filtering area in a filter of simple and conventional design, such as a flat filter of rectangular shape.

Another object is to achieve compactness, particularly in the breadth of the unit from front to rear.

To meet the above several requirements, the invention contemplates the arrangement of fan, filter, and heat transfer unit relative to the casing substantially as follows: the fan and filter are each made relatively thin, are positioned in substantially vertical planes extending longitudinally of the casing, are horizontally opposite each other, one in front of the other, and extend substantially the same distance in a vertical direction, occupying a major portion of the height of the casing; the filter is extended from end to end of the casing and is spaced from the inlet of the fan just enough to insure ample space for air to travel from the remote regions of the filter to the fan inlet; and the heat transfer unit occupies the remainder of the height of the casing.

45 In the preferred form of the invention, the filter is inclined somewhat from the vertical so that one of its horizontal edges is quite close to the fan, leaving an opening of maximum area between said edge and the adjacent wall of the casing, for air to pass from the heat transfer element into the space behind the filter, the other horizontal edge of the filter being quite close to the said wall of the casing so as to provide maximum space between the filter and the fan for the air to flow from the end region

of the filter into the fan intake; and the fan supporting bracket is accommodated in the same space between the fan and the filter, whereby the rear side of the fan may be positioned closely adjacent the opposite wall of the casing.

5 The invention further aims to provide a conditioner that is relatively simple and inexpensive in construction.

Other objects are: to provide for removal of the filter; to provide means for guiding the filter 10 back to its inclined position during replacement; to provide closure means for normally closing off the space between the filter and the fan, but capable of being moved aside to allow access to the fan bearings; and to provide a fan supporting 15 bracket of such construction as to accommodate itself in the aforementioned space between the fan and filter, to support the motor beyond the periphery of the fan, and to constitute a bracing strut rigidifying the casing as a whole.

20 Another object is to provide means for disposing of water of condensation, requiring no drain pipes.

Another object is to provide a novel casing structure of which end panels of the heat transfer element form a part.

With these and other objects in view my invention consists in the combination and construction and arrangement of the various parts thereof, whereby the objects contemplated are attained, 30 as more fully set forth in the accompanying specifications, pointed out in my claims, and illustrated in the accompanying drawings, in which:

Fig. 1 is a rear elevation, partly in section, of an air conditioner embodying the invention.

Fig. 2 is a central vertical sectional view through the same.

Fig. 3 is a detail sectional view taken on the line 3—3 of Fig. 1.

Fig. 4 is a view similar to Fig. 2, of a somewhat 40 modified form of the invention.

Fig. 5 is a similar view of a further modification of the invention.

Fig. 6 is a vertical longitudinal sectional view of one end of the conditioner shown in Fig. 5.

Fig. 7 is a view similar to Fig. 2, of a further modified form of the invention.

Fig. 8 is a detail view of the central region of the filter, partially raised, and associated portions of the fan bracket.

The conditioner shown in Figs. 1 and 2 comprises generally a heat transfer unit A, a filter B, a fan C, and a casing D, the latter being in each case roughly subdivided vertically in a horizontal plane indicated at 9 into a large compartment 10, 55

accommodating the fan and filter, and a small compartment 11, in which is located the heat transfer unit A.

The casing D comprises, in Figs. 1 and 2, the front wall 13, the bottom 14, the end walls 15, and the rear wall 16, the latter terminating at the plane 9 to form the casing inlet 60.

End panels 17, constituting part of the heat transfer unit A, form continuations of the end walls 15. The panels 17 are pan shaped, having marginal walls 18, 18a, 19 and 20 defining a space in which are accommodated the return bends 28 which connect together the ends of the vanned tubes of the element A. The tubes project through 15 the panels 17.

The walls 18 are secured to the front wall 13 of the casing. The walls 19 are supported upon and secured to the base rails 21. The walls 20 are secured to and support a partition 22 extending from end to end of the casing, dividing the space 10 from the space 11 on one side thereof, and forming the bottom of the fan housing. Air concentrating baffles 23 are interposed between the panels 17 and the rails 21 and partition 22 respectively.

The heat transfer coil A fills the space between the partition 22 and the lower baffle 23. The latter has a rear flange 24 forming a drip collecting eave from which condensate may pass through 30 holes 25 to the collecting pan 26, positioned between the bottom 14 and the partition 23. The pan 26 is in the form of a drawer, slideable on the bottom 14, and removable for emptying its contents.

35 The bottom marginal wall 19 of the panel 17 has its edge turned up as at 27, forming a collecting eave for collecting condensate from the return bends 28 of the coil A. Collected moisture flows through openings 29 into the eaves 23, 24. The 40 upper walls 20 of the panels 17 are bent upwardly to form flanges 30, which are welded or otherwise suitably secured to the end walls 15. The bottom 14 is secured to the inner faces of the rails 21.

The element A is connected to a suitable refrigerating machine or heat generating source, by lead in tubes 31 extending downwardly in the space in the panels 17, and through the bottom 14.

50 The fan housing occupies the space directly above the element A, being defined by the rear casing wall 16, the end casing walls 15, the bottom partition 22, and a fan inlet shroud 33, extending from end to end of the casing. The shroud 33 has a central opening 34 which registers with the inlet 35 of the centrifugal fan C.

55 The closed side 36 of the fan or impeller C is mounted upon the fan pulley 37 which in turn has a hub 38 mounted on the fan shaft 39. The shaft 39 is journaled in a bearing 40 mounted on the fan bracket 41.

60 The space in the compartment 11 not occupied by the element A communicates with and is directly below the space between the fan housing and the front wall 13 of the conditioner casing D. The latter space is traversed by the filter B, 65 so that the air issuing from the element A, will pass through the filter on its way to the fan C. In order to achieve maximum filtering area in a filter of conventional and simple design, the filter is positioned nearly upright extending from top to bottom of the fan, but inclined enough from the vertical so that its lower edge will lay over against the fan housing while its upper edge substantially meets the front wall 13. The filter extends the full length of the casing. Thus there 70 will be formed between the filter and the fan

shroud 33, a wedge shaped space 42 having its largest volume opposite the upper region of the filter, to accommodate the flow of air through the end regions of the filter and to the fan inlet. This space is important in view of the fact that a major portion of the area of the filter lies beyond the mouth of the fan.

As a further consequence of the inclined position of the filter, the horizontal cross sectional area of the space 43 through which the air reaches the filter, is graduated from a maximum at its lower extremity, through which the entire volume of air passes, to a minimum at the upper extremity whereat all of the air has passed through the filter. The space 43 at its lower extremity thus occupies the entire distance from the front wall 43 to the fan shroud 33.

The space 42 further serves to accommodate the bracket 41 extending from end to end of the casing and secured to the end walls 15 as at 44, 20 thus serving as a longitudinal strut in addition to supporting the fan.

The bracket 41 includes an upstanding pedestal 45, on which is secured the motor 46. The top of the pedestal 45 extends rearwardly above the cut 25 away region of the shroud 33, the remainder of the pedestal and the bracket 41 lying forwardly of the shroud.

A motor housing is formed by a plate 47 interposed between the pedestal 45 and the motor 46, 30 and an end wall 48 projecting upwardly from the inner end of the plate 47. A flange 19 on the end wall 48 secures the latter to the rear side of the shroud 33. The purpose of the motor housing is to close off the top of that portion of 35 the space 42 which lies below the motor 46, to prevent short circuiting of air currents from discharge to intake of the fan.

The remainder of the space 42 is closed at the top by a cover 50, hinged at 51 by means of ears 40 52 to a bracket 53 secured to the end wall 48 of the motor housing, and to the end wall 15, respectively.

The filter is retained by a channel 54 formed between the upper baffle 23 and the shroud 33, 45 and angle guides 55 having flanges 56 engaging the rear sides of the ends of the filter. Inclined guides 57 catch the two lower corners of the filter as it is lowered through the restricted spaces between the front wall 13 and the upper ends of 50 the guides 55, and cause the lower region of the filter to slide laterally until it slips into the channel 54. The cover 50 may be lifted to give better access to the filter for removal. The cover 55 also gives access to the bearing 40 for lubrication purposes.

The motor 46 carries the drive pulley 58 which drives the fan pulley 37 by means of a V-belt 59.

The heat transfer element compartment 17 may be above the filter-fan compartment, as in Fig. 4. 60 In this case, the wedge shaped space 43 communicates at its lower extremity with the casing inlet 60 instead of with the space 17 as in Fig. 2. The space 42 and fan supporting bracket 41 are the same as in Fig. 2 except that they are 65 positioned lower in the casing. The motor 46 is positioned just below the condensate pan 26 which in this case is at the upper extremity of the fan, and forms the removable closure for the top of the space 42. Its ends are supported by 70 guides 61.

The heat transfer element A is positioned vertically, in the center of the space 17, just above the pan 26. Air issuing from the fan passes through the compartment 11 and the element A as 75

indicated by the arrows. The filter is removable through the pan opening 26a.

Another form of the invention is shown in Figs. 5 and 6. In this form, the filter meets the shroud 33 at its upper extremity, and meets the rear wall 16 at its lower extremity. The casing inlet 60 is disposed intermediate the top and bottom of the casing, at the upper extremity of the filter, and air passes downwardly through the filter instead of upwardly as in Figs. 3 and 4. The motor is mounted on the bottom 14 of the casing.

The element A extends horizontally entirely across the compartment 17, and condensate is collected by a plurality of eaves 62 underlying alternate tiers of the tubes composing the element A, while drain sheds 63 underlie the remaining tiers of tubes and overlie the edges of the eaves 62, being spaced sufficiently thereabove to allow ample circulation between them.

The eaves 62 extend through openings 64 in one of the panels 17, through which the condensate flows to a trough 65 within the panel. A Venturi pump 66, in one of the lead in tubes 31, withdraws the moisture from the trough 65 through a suction tube 61, and injects it into the heat transfer fluid. It may thence be ejected at the refrigerator by a suitable relief valve.

The rear wall 16 in this case may be hinged at 68, and lowered to allow removal of the filter, which in turn gives access to the motor.

In the embodiment shown in Figs. 7 and 8, the filter is positioned in a vertical plane, and the fan bearing passes through it. In order that the filter may be removed, it is slotted as at 68 from the place where it accommodates the fan bearing to its lower edge, and the bearing has a depending tenon 69 which fills the slot 68. The tenon 69 may have its edges channelled as at 70 to hold the edges of the filter defining the slot 68.

In this case the motor and drive mechanism are positioned in the space on the opposite side of the filter from the fan, as is the fan bracket also.

I claim as my invention:

1. In an air conditioner, an elongated upright casing, relatively narrow from front to rear, providing in its interior two vertically superimposed chambers each extending longitudinally thereof, and having intake and discharge openings communicating respectively with said chambers, a relatively thin, large diameter slow speed centrifugal fan and a filter, together occupying one of said chambers, each positioned in a substantially vertical plane extending longitudinally of the casing, one behind the other, the intake side of the fan facing the filter, a heat transfer element traversing the other of said chambers between its associated casing opening and the filter, and means to direct air through the filter and thence into the fan.

2. In an air conditioner, a substantially rectangular casing, relatively narrow in one dimension, providing in its interior two chambers divided by a plane transverse to the casing, and having inlet and discharge openings communicating respectively with said chambers, a relatively thin, large diameter slow speed centrifugal fan and filter, together occupying one of said chambers, each positioned substantially perpendicular to said plane and substantially parallel to the major sides of the casing and to each other, one behind the other, the intake side of the fan facing the filter, a heat transfer element traversing the other of said chambers between its associated

casing opening and the filter, and means to direct the air through the filter and thence into the fan.

3. In an air conditioner, a substantially rectangular casing, relatively narrow in one dimension, providing in its interior two chambers divided by a plane transverse to the casing, and having inlet and discharge openings communicating respectively with said chambers, a relatively thin, large diameter, slow speed centrifugal fan and filter, together occupying one of said chambers, each positioned substantially perpendicular to said plane and substantially parallel to the major sides of the casing and to each other, one behind the other, the intake side of the fan facing the filter, a heat transfer element traversing the other of said chambers between its associated casing opening and the filter, and means to direct the air through the filter and thence into the fan, said filter being positioned so that its edge nearest the inlet is positioned closely adjacent the fan so as to provide ample area of communication between the inlet and the space between the filter and the adjacent casing wall on the side of the filter remote from the fan.

4. In an air conditioner, a substantially rectangular casing, relatively narrow in one dimension, providing in its interior two elongated chambers divided by a plane transverse to the casing and having inlet and discharge openings communicating respectively with said chambers, a relatively thin, large diameter, slow speed centrifugal fan and filter, together occupying one of said chambers, each positioned substantially perpendicular to said plane and substantially parallel to the major sides of the casing and to each other, one behind the other, the intake side of the fan facing the filter, a heat transfer element traversing the other of said chambers between its associated casing opening and the filter, and means to direct the air through the filter and thence into the fan including a fan intake shroud positioned between the fan and filter, extending from end to end of said chamber in which the fan and filter are located, and having an opening registering with the fan intake and a partition wall extending substantially in said plane from said shroud to the major wall of the casing which is adjacent the fan.

5. In an air conditioner, a substantially rectangular casing, relatively narrow in one dimension, providing in its interior two elongated chambers divided by a plane transverse to the casing, and having inlet and discharge openings communicating respectively with said chambers, a relatively thin, large diameter, slow speed centrifugal fan and filter, together occupying one of said chambers, each positioned substantially perpendicular to said plane and substantially parallel to the major sides of the casing and to each other, one behind the other, the intake side of the fan facing the filter, a heat transfer element traversing the other of said chambers between its associated casing opening and the filter, and means to direct the air through the filter and thence into the fan including a fan intake shroud positioned between the fan and filter, extending from end to end of said chamber in which the fan and filter are located, and having an opening registering with the fan intake and a partition wall extending substantially in said plane from said shroud to the major wall of the casing which is adjacent the fan, the filter extending beyond the fan inlet at both ends and being so inclined and of such breadth that one of its longitudinal edges is positioned closely adja-

cent said shroud while its opposite edge is at a distance from the shroud, whereby to give maximum area of communication between the inlet and the chamber between the filter and adjacent casing wall, while providing also a chamber between the filter and the shroud for air currents to pass from the end regions of the filter to the fan inlet.

6. In an air conditioner, a substantially rectangular casing, relatively narrow in one direction, providing in its interior two elongated chambers divided by a plane transverse to the casing, and having inlet and discharge openings communicating respectively with said chambers, a relatively thin, large diameter, slow speed centrifugal fan and filter, together occupying one of said chambers, each positioned substantially perpendicular to said plane and substantially parallel to the major sides of the casing and to each other, one behind the other, the intake side of the fan facing the filter, a heat transfer element traversing the other of said chambers between its associated casing opening and the filter, and means to direct the air through the filter and thence into the fan including a fan intake shroud positioned between the fan and filter, extending from end to end of said chamber in which the fan and filter are located, and having an opening registering with the fan intake and a partition wall extending substantially in said plane from said shroud to the major wall of the casing which is adjacent the fan, the filter being parallel to the shroud and spaced intermediate the shroud and the adjacent casing wall but closer to the shroud than to said wall.

7. In an air conditioner, an upright casing, relatively narrow from front to rear, providing in its interior two vertically superimposed chambers, the casing having at its top a discharge vent communicating with the upper of said chambers, and at its bottom an inlet communicating with the lower chamber, a relatively thin, large diameter, slow speed centrifugal fan and a filter, together occupying the upper chamber, each positioned in a substantially vertical plane extending longitudinally of the casing, one behind the other, the intake side of the fan facing the filter, a heat transfer element traversing the lower chamber between the inlet and the filter, and means to direct air issuing from said element, through the filter and thence into the fan.

8. In an air conditioner, an upright casing, relatively narrow from front to rear, providing in its interior two vertically superimposed chambers, the casing having at its top a discharge vent communicating with the upper of said chambers, and at its bottom an inlet communicating with the lower chamber, a relatively thin, large diameter, slow speed centrifugal fan and a filter, together occupying the upper chamber, each positioned in a substantially vertical plane extending longitudinally of the casing, one behind the other, the intake side of the fan facing the filter, a heat transfer element traversing the lower chamber between the inlet and the filter, and means to direct air issuing from said element, through the filter and thence into the fan, said means including a shroud positioned between the filter and fan and apertured in registry with the fan intake and a partition extending from the lower extremity of the shroud between the heating element and fan to the major casing wall that is adjacent the fan, the filter being inclined so that its lower edge meets the corner substantially between said shroud and partition while its upper edge sub-

stantially meets the adjacent major casing wall, the filter extending beyond the fan inlet at both ends.

9. In an air conditioner, an upright casing, relatively narrow from front to rear, providing in its interior two vertically superimposed chambers, the casing having at its top an inlet communicating with the upper of said chambers and at its bottom an outlet vent communicating with the lower chamber, a relatively thin, large diameter, slow speed centrifugal fan and a filter, together occupying the lower chamber, each positioned in a substantially vertical plane extending longitudinally of the casing, one behind the other, the intake side of the fan facing the filter, a heat transfer element traversing the upper chamber between the inlet and the filter, and means to direct the air flow in said casing through the filter and thence into the fan intake.

10. In an air conditioner, a casing providing a chamber which is divided by a fan intake shroud into two compartments the dimensions of which are considerably greater in directions parallel to the plane of said shroud than in the direction perpendicular to said shroud, said shroud having an opening, a relatively thin, large diameter, slow speed centrifugal fan in one of said compartments, positioned closely parallel to said shroud, its intake registering with said opening, and a filter in the other compartment extending at both ends beyond said intake, substantially parallel to said shroud, and fairly closely adjacent thereto, just enough space being provided between the filter and the shroud to give ample room for air flow from the end regions of the filter to said opening.

11. In an air conditioner, a casing providing a chamber which is divided by a fan intake shroud into two compartments the dimensions of which are considerably greater in directions parallel to the plane of said shroud than in the direction perpendicular to said shroud, said shroud having an opening, a relatively thin large diameter, slow speed centrifugal fan in one of said compartments, positioned closely parallel to said shroud, its intake registering with said opening, and a filter in the other compartment extending at both ends beyond said fan intake, said filter being substantially parallel and closely adjacent to both the shroud and the opposite wall of said compartment, just enough space being provided between the filter and the shroud to give ample room for air flow from the end regions of the filter to said opening.

12. In an air conditioner, a casing providing a chamber which is divided by a fan intake shroud into two compartments the dimensions of which are considerably greater in directions parallel to the plane of said shroud than in the direction perpendicular to said shroud, said shroud having an opening, a centrifugal fan in one of said compartments, positioned closely parallel to said shroud, its intake registering with said opening, and a filter in the other compartment extending at both ends beyond said intake, substantially parallel and closely adjacent to both the shroud and the opposite wall of said compartment, just enough space being provided between the filter and the shroud to give ample room for air flow from the end regions of the filter to said opening, said fan being relatively thin, of large diameter, and devoid of any circumferential shroud other than the walls of said compartment, one side of said compartment having a full length discharge vent.

13. In an air conditioner, a casing providing a chamber which is divided by a fan intake shroud into two compartments the dimensions of which are considerably greater in directions parallel to the plane of said shroud than in the direction perpendicular to said shroud, said shroud having an opening, a centrifugal fan in one of said compartments, positioned closely parallel to said shroud, its intake registering with said opening, and a filter in the other compartment extending at both ends beyond said fan intake, substantially parallel and closely adjacent to both the shroud and the opposite wall of said compartment, just enough space being provided between the filter and the shroud to give ample room for air flow from the end regions of the filter to said opening, said fan being relatively thin and of large diameter, a large pulley secured to the fan shaft adjacent the casing wall, a motor, mounted in a space cut out of the shroud at one corner thereof, a small pulley on the motor, and a belt connecting said pulleys and adapted to drive said fan at a slow speed.
14. In an air conditioner, a rectangular casing, a flat filter therein, a centrifugal fan positioned with its intake closely adjacent and substantially parallel to said filter, a driven pulley on the closed side of the fan, a motor, a drive pulley thereon, and a belt traveling on said pulleys in a plane parallel to said fan, the motor being positioned in a corner of the casing beyond the periphery of the fan, its shaft intersecting the plane of the fan.
15. In an air conditioner, a casing and a silently operating centrifugal fan therein comprising a non-peripherally shrouded, large diameter impeller, and means to rotate said impeller at a relatively slow speed including a motor and a belt drive, the motor axis parallel to the impeller axis and the belt lying in a plane parallel to that of the impeller.

LACHLAN W. CHILD.
